PICTURE REPRODUCING APPARATUS

Henry Shore, Elizabeth, N. J., and James N. Whittaker, Tuckahoe, N. Y., assignors to Radio Corporation of America, a corporation of Delaware

Application August 22, 1931, Serial No. 558,750

18 Claims. (Cl. 178—5)

The present invention relates to a method and apparatus for transmitting intelligence, which is preferably in the form of a picture record, to a remote point where an electro-optical image or likeness of the transmitted subject is to be reproduced. Broadly speaking, the invention is one which is capable of transmitting any type of intelligence but is particularly directed to the transmission of subjects which can be observed by the eye. These subjects, for example, may be pictures, copies of newspapers, financial statements, film records, such as motion picture film with or without sound accompaniment, fashion plates, copies of finger prints, drawings, or other similar matter.

Broadly speaking, the invention will herein be characterized as a constant frequency variable dot system by the use of which printed subject matter or the like may be transformed into a series of electrical impulses which, when received over a radio or a wire line communication channel, may be utilized for reproduction purposes. The constant frequency variable dot system of transmission consists essentially in the conversion of amplitude changes of a carrier or tone frequency into varying weight signalling or marking impulses which are transmitted at constant frequency and amplitude so that the useful period of transmission, which will at the receiving point correspond to marking periods, may have any value varying between zero and 100 percent.

In the systems known at present for accomplishing the transmission desired over the lighter portions of the subject for transmission, that is, over portions of the subject varying in intensity between middle gray and white for example, the marking periods are usually of constant duration while the spacing periods vary, and as the intensity of light and shadow on the subject varies between middle gray and black for example, the type of marking to reproduce these particular tonal values of the subject changes to a marking of variable duration with equal spacing between each marking representation. With the type of marking now used to denote the lighter portions of the picture, the relationship between the marking and spacing periods may vary from equality of marking and spacing periods to as much as fifty times the time duration of spacing to the time duration of marking, whereas for the darker portions of the record the time duration of the marking impulses with respect to the spacing impulses may vary from equality to fifty times the time duration of the spacing im-

pulses. Thus, it is seen that, in addition to varying weights of marking impulses, the frequency at which these impulses are transmitted is varying and with the usual type of equipment now in use for transmitting records of this type this variation in frequency range may be, for example, between fifty and three hundred and fifty cycles per second.

According to the present invention, it is desired to transmit signals which will be reproduced as marking impulses always at a constant frequency, so that the number of marking impulses per unit of time is constant, that is, the sum of the marking and spacing duration for any value of density is always constant but the marking duration depends upon the density of the subject at the point of scanning. Suppose, for example, that it is desired to transmit one hundred and fifty dots per second and for a light portion of the subject the marking interval might be $1/1500$ of a second, then it is seen that the spacing duration would be $9/1500$ of a second. However, for a dark portion of the record the conditions might be such that the marking pulses occur for $7/1500$ of a second whereas the spacing was reduced to $3/1500$ of a second. In both of these cases it would be noted however that the sum of the marking and spacing time periods is always $1/150$ of a second, or if the one hundred and fifty dots per second first assumed is the screen frequency, then it is seen that the sum of the marking and spacing impulses per time unit is always the reciprocal of the screen frequency.

This system of transmission exerts less strain upon the radio transmitter than the system previously used, since the required range of harmonics of the keying frequency is reduced. This applies to the radio receiver as well.

The theory of operation upon which a system of the type to be hereinafter disclosed is predicated may be given substantially as follows: The output of the scanning head, which includes the usual photoelectric element for converting the variable intensities of light and shadow on different and successive elemental sections of the picture record for transmission into corresponding or proportionate electric current impulses and which light from the picture as it influences the photoelectric element is interrupted at a predetermined rate, for example 3500 cycles, to introduce a tone carrier into the output of the photoelectric element, will be an amplitude modulated carrier of the tone frequency. It is to be understood, however, that any suitable form of

apparatus for producing the tone frequency may be used, for example, a bridge arrangement may be supplied wherein there are two or more tubes to which a tone frequency is fed and across which the tone frequency may be taken out. In such an arrangement the photo cell is connected across one diagonal of the bridge arrangement and as the cell becomes illuminated, or darkened, it serves to unbalance the bridge. Another system for producing the tone frequency may be provided by using what is known as the modulated type of scanning device wherein the carrier tone frequency is coupled to the input of the photo cell amplifier tube. In such a system, forming a portion of the tube input circuit, there is a resistor element series-connected between the amplifier tube filament and the grid, and across the resistor the photo cell and its battery are connected, so that if the amplifier tube is arranged to operate near the cut-off point the variations in illumination upon the photo cell produces a variation of bias on the grid of the amplifier tube which changes the amplified current output thereof.

This amplitude modulated output energy is at a relatively low signal level which must then be amplified to be put to any useful purpose. After the picture modulated photo cell current is properly amplified, the resulting amplitude modulated tone frequency carrier is then rectified and the rectifier output resistor is made sufficiently high to insure an essentially linear output. The output energy from this rectifier may then be directed to what we will hereinafter describe as a "converter", which comprises a mixing tube or modulator and a square wave amplifier, which latter element has been shown, described and claimed in U. S. Patent No. 2,005,111 issued to Henry Shore on June 18, 1935, and entitled "Amplifier."

In this proposed system, as in the usual type of facsimile apparatus, the record or subject for transmission is carried upon a record holder or drum which is driven from any suitable form of motor and with the present system, in addition to driving the picture record holder, provision is made for rotating a tone generator, the output of which is arranged to be fed into the mixing tube along with the rectified picture signal. However, by the present system as proposed, the mixing tube is preferably so biased that the screen tone does not actuate the grid throughout its entire cycle, that is, the output of the rectifier when scanning a white portion of the picture blocks completely the screen tone from passing through, whereas a medium gray will permit but half of each cycle to get through, and a black will permit the complete cycle to actuate the grid. The square wave amplifier which is energized from the output of the mixing tube is arranged so as to convert this output energy into constant amplitude pulses of varying width, the width, of course, depending upon the amplitude of the mixing tube output. The impulses appearing in the output of the square wave amplifier may then be used to key a tone or carrier frequency. The resultant tone or carrier frequency signal is then placed upon a transmission line or channel suitable for keying a radio transmitter or a wire line distribution system.

From the above analysis of the system and brief description of the functioning thereof, it is seen that the type of picture which will result

from such an arrangement resembles variable width recording which, while it gives a very presentable representation when held some distance away from the eye, gives a loss in detail when inspected closely. To overcome this difficulty, a phase shift of 180 degrees of the screen tone is introduced on alternate traversals of the picture subject by the scanning element. This reversal produces at the receiving point a picture which closely resembles a half tone or which is more pleasing to the eye and which will preserve the detail of the original subject for transmission. In this way, the system is arranged to produce a screen structure which resembles the photographic half tone process while accomplishing results electrically. However, it should be noted that for black and white transmission, the screen frequency need not be used, nor need the double setting be used, but even with this type of transmission the use of the converter unit is advantageous due to the inclusion therein of the square wave amplifier.

From the brief and general statement above of the principles of operation of the invention, it will be seen that we have sought, as a primary object of the invention, to develop a system in which improved quality of the received records is obtainable.

A further object of the system is to provide a system which is easy to maintain and to operate and which will function at increased working speeds.

Still a further object of the invention is to eliminate from the transmission of record subjects substantially the entire personal element. This is made possible by eliminating completely all biasing batteries. The elimination of all of the biasing batteries tends to reduce maintenance cost and, at the same time, tends to maintain the apparatus always in a condition ready to work without the necessity of making a series of preliminary adjustments where the circuit has been idle for a considerable period of time as would be the case where batteries or the like are used in the system.

A further object of our invention is to provide a system for converting the varying intensities of light and shadow of the elemental sections of a record subject into proportionate strength electric current impulses and to adapt the system to high speed keying in a manner which will hereinafter become apparent.

Further objects of the invention are to provide for accuracy and stability of operation while maintaining a relatively simple and fool-proof arrangement of circuits capable of transmitting electric current impulses which may be re-converted into a recording of increased detail and accuracy.

Still other and further objects of the invention will suggest themselves and become apparent to those skilled in the art to which the invention relates by making reference to the accompanying drawings, wherein:

Fig. 1 illustrates conventionally one form of circuit arrangement for providing the transmission facilities but omitting from the showing the tone generation and the initial conversion of the picture record intensities into electric current impulses;

Fig. 2 is a diagrammatical showing to represent the sequence of the various operations in the device;

Fig. 3 represents a form of record adapted to

be received as the result of transmission by the system disclosed in Fig. 1. In Fig. 3 the portion *a* represents, reading from left to right, the change from white to black and back to white for four successive lines of recording, while portion *b* represents the same change in intensity but modifies the showing of Fig. 3*a* by providing a double setting whereby alternate lines of the recording are displaced by one hundred and eighty electrical degrees, or, in other words, the marking of alternate lines takes place half way between each of the markings of the preceding and following line;

Fig. 4 represents a suitable means for producing the double setting or phase shift to change the marking characteristics of the system from the form shown by Fig. 3*a* to that shown by Fig. 3*b*; and

Fig. 5 is a diagrammatic showing of a suitable form of receiving device for receiving picture signals transmitted by the system shown in Fig. 1. Figure 5 indicates a receiving system of the diversity type as controlling the recording in the photoradio recorder unit, which is to be understood as including either photographic or visual recording.

Now, to make reference to the drawings, and first to refer to Fig. 2 thereof, a subject for transmission has been illustrated as consisting of a record strip varying in intensity from left to right from white to black. This record or subject, when an electro-optical image representation is to be transmitted, is placed upon a record holder or support of any suitable design and character. The successive elemental areas of the subject are assumed to be exposed to illumination which, when it affects the photoelectric light converting element, will produce corresponding or proportionate changes in the output current from the cell, the greatest current, of course, being obtainable from high lights on the picture due to a maximum transmission of light through the picture or reflection of light from the picture, and the minimum output occurring with black due to the fact that the light is blocked from passing through the picture or absorbed so as to prevent reflection from the picture, depending, of course, upon whether direct or indirect illumination is resorted to.

In well known manner, the amplitude controlled picture frequencies occurring at a rate corresponding to the rate of interruption of the light directed toward the photo cell are amplified, after which they may be rectified and supplied to a converter unit which comprises a mixing tube and a square wave amplifier. Jointly with the application of the amplitude controlled picture frequencies being brought upon the converter, a synchronized screen tone of a frequency depending upon the detail desired is supplied to the converter, and the resulting output from the square wave amplifier forming a portion of the converter is then directed to a line tone carrier frequency in the form of a modulator tube or tubes to which is also supplied the line tone carrier frequency. For line transmission work, this frequency may be a relatively high audio or supersonic frequency, and for direct radio transmission the line tone oscillator may be of a radio frequency. The lower portion of Fig. 2 shows at *a* the varying amplitude picture frequency occurring in the output from the amplifier as varied by changing from white to black on the picture subject, and it will be noted that the amplitude of the tone frequency is decreasing con-

tinuously. The portion *b* immediately below the diagrammatic showing of the rectifier indicates the envelope of the rectified output showing a continually decreasing amplitude pulse. Portion *c* of Fig. 2 shows the output from the square wave amplifier portion of the converter unit and depending upon the amplitude of the rectified signal the duration of the marking, as identified by the portions *m*, *n*, etc., is determined. These converter outputs of constant amplitude but variable duration then serve to key the oscillator frequency which is transmitted as an interrupted carrier of constant amplitude but variable time duration depending upon the marking. The resultant marking is shown by Fig. 3 where the successive lines reading from left to right are produced as impulses of varying width but occurring at constant frequency so that the recording takes place along successive vertical lines, as shown by Fig. 3 of the drawings. So arranged, light portions of the record will be produced merely as a dot, whereas for middle grays the dot is elongated into a rather short line and the spacing between successive markings is substantially equal, while for the black portions there is substantially no spacing between the markings which appear to occur for the entire available time period with the result that the marking is substantially continuous, as shown by the right hand portion *r* of Fig. 2, where the carrier or line tone oscillator frequency appears to be uninterrupted for a considerable length of time.

To refer now specifically to Fig. 1 of the drawings, showing a preferred system and circuit for accomplishing the results above outlined with respect to Fig. 2 and portion *a* of Fig. 3, the screen tone frequency, as generated in accordance with the arrangement of Fig. 4, for example, is applied to the terminals 1 and 3 from which this energy is directed by means of conductors 5 and 7 to the primary winding 9 of a transformer 11 and then transferred to the secondary winding 13 of the transformer to the input circuit of the vacuum tube 15 including input electrode 17. The output energy from the vacuum tube 15 is directed to the primary winding 19 of a transformer 21 from which it is transferred by means of the secondary winding 23 to a potentiometer 25. By means of the adjustable contact 27 of the potentiometer the screen tone as now amplified by the amplifier 17 is supplied with desired amplitude strength to the input electrode 29 of the mixing tube 31. The potentiometer thus controls the bias on tube 31 in accordance with the setting of the adjustable contact 27. Plate potential for the amplifier 17 is supplied through a conductor connected at one end to one terminal of the primary winding 19 of the transformer 21 and connected at the other end to a resistor 20 to regulate the plate voltage. The plate voltage is supplied from a terminal point 28 to resistor 20 and thus to tube 15.

Simultaneously with the application of the screen tone to the amplifier 15, the input signals coming from the photo-cell-amplifier, which are in the form of variable amplitude signals of constant frequency, the frequency being dependent upon the chopper frequency (not shown) influencing the photo cell, are supplied to the terminals 33 and 35 from which they are directed by means of conductors 37 and 39 to a potentiometer 41. These fluctuating picture record signals may be controlled as to their effective amplitude by means of the adjustable potentiometer 75

contact and then supplied to the primary winding 43 of transformer 45, from the secondary 41 of which these input frequencies are impressed upon the input circuit of the amplifying tube 49 including electrode 51. The tube amplifier 49 derives its plate potential from the source, connected to the terminal 26, through a filter circuit comprising series-connected inductance elements 55 and shunt-connected capacity elements 57, 59, which in turn connect with a conductor 61 leading to the terminal point 26. The output energy from the amplifier 49 is fed through the primary winding 53 of transformer 55 from the secondary 67 of which the amplified energy is directed to the vacuum tubes 69, 71 serving together as full wave rectifiers. The tubes 69 and 71 are of the usual alternating current type having their grid and plate elements 73, 75 and 73', 75' respectively tied together. This connection is to avoid any direct connection as would be present with the usual type of full-wave rectifying tubes in common use. Across the output of the rectifier unit comprising the tubes 69 and 71 is shunt resistor 77 and in series with the output are inductance elements 79, 79' shunted by capacities 81, 81'. Across the entire output from the rectifier combination is a resistor 83 and potentiometer 85. From the variable contact of the potentiometer a conductor 87 connects the resulting rectified picture signal input with the potentiometer 25, and by means of the adjustable contact this amplified and rectified picture signal input is supplied jointly with the screen tone to the mixing tube 31 in such a manner as to control the period when the screen tone renders the amplifier 31 operative in accordance with the tonal value of the picture as represented by the signal supplied from the rectifier.

The plate element 91 of the mixing tube 31 is supplied with plate potential through resistors 93, 95, 97, 99 and 101 which are connected with the terminal 26 serving as the source of plate potential supply. Connected with the output circuit of the mixing tube 31 are the tubes 105 and 113 serving together as a square wave amplifier unit. The grid element 103 of the first tube 105 of the square wave amplifier is energized in accordance with the output signal flowing from the mixing tube 31.

As was explained in the U. S. Patent No. 2,005,111 issued to Henry Shore, issued June 18, 1935, and entitled "Amplifier", the output current from the first tube 105 of the square wave amplifier flows in the circuit from the plate element 107 through the resistor element 109 to the source 26 of plate potential for the tube 105 and then back to cathode in the usual manner. In accordance with the strength of current flowing in the tube 105, varying voltage drops are produced in the resistor 109. These varying voltage drops, in turn, control the potential on the grid element 111 of the second tube 113 of the square wave amplifier which is tied directly to one end terminal of the resistor element 109. With a heavy current passing through the tube 105 it is seen that there will be a substantial voltage drop occurring in the resistor 109 with the upper end of resistor 109, as shown, becoming more negative, so that the grid element 111 of the tube 113 acquires a decidedly negative bias which tends to cut off the plate current flow through the second tube 113 of the square wave amplifier. When conditions are reversed, so that there is a decrease in the current flow through the tube 105, the upper end of the resistor element 109 is car-

ried positive with respect to its previous potential so that the grid element 111 of the second tube 113 of the square wave amplifier tends to assume a potential positive with respect to the potential acquired for a maximum current flow through the first tube of the square wave amplifier unit. This causes the second tube 113 to commence to draw plate current so that, by means of the connection 119 from the plate element 115 of the second tube 113 through the capacity 121 which is tied to the grid 103 of the first tube 105 of the square wave amplifier unit, each increase in plate current strength flowing through the tube 113 tends to decrease, at a rate more rapid than normal, the current flow through the first tube 105 of the unit so as to bias the first tube substantially to cut-off irrespective of the rate at which the signal intensity supplied to the first tube decreases. The second tube 113 of the square wave amplifier unit draws its plate potential through a resistor 117 connected through a second resistor 101 to the source of plate potential supply connected to the terminal 26.

In order to determine the character of the signal forming the useful output from the square wave amplifier unit a switch 127, which has terminals 123 and 125 connecting with the upper end of resistors 117 and 109 respectively, has been provided so that the useful output may be that from either the first tube 105 or the second tube 113 of the square wave amplifier, depending upon whether the switch arm 127 rests against the lower or upper switch contact point. The output energy thus controlled is directed from the switch arm 127 through a conductor 129 to a second switch 131, which is normally resting against the right hand contact point, looking at Fig. 1. The switch 131 connects through a conductor 137 to the midpoint of the secondary winding 139 of the transformer 141 to energize in a substantially cophasal manner the grids 173 and 177 of the push-pull connected tubes 179 and 181 which form a part of the line tone keying unit.

The line tone oscillator tube 143 is provided with the usual electrode elements comprising a plate element 144, a grid element 150, and the usual electron source or cathode. The plate element 144 of the oscillator tube 143 is connected with a capacity element 145 which in turn connects through resistor element 147 and an inductance 149 to the grid element 150. Plate potential is supplied to the oscillator tube 143 through a choke 153 connecting through a resistor 151 with the source of plate potential connected with the plate potential supply terminal 26. Shunting the inductance element 149 is a capacity element 155, in shunt with which is also a second capacity 157 which may be connected in circuit with the oscillatory circuit, comprising the inductance 149 and capacity 155, by closing the switch 158. Any closure of the switch element 158 to connect the second capacity in shunt with the first capacity will, of course, change the natural frequency of operation, as is desirable under certain conditions where it is necessary to change the line tone frequency. Also connected across the grid circuit of the oscillator tube 143 is another capacity element 151 which connects at one end to the filament of the tube 143 and at the other end adjustably to a point on the inductance element 149, which point is grounded at 173. The output from the oscillator tube 143 is fed through a resistor 161 and potentiometer 163 to the primary winding 169 of the

transformer 141. Prior to supplying the oscillatory energy to the transformer 141, the strength or amplitude of the oscillating signal may be controlled by changing the location of the variable contact 165 of potentiometer 163 to control the amount of energy supplied through the conductor 167 to the primary winding 189 of the transformer 141. As the oscillator frequency and the output signal from the square wave amplifier unit are simultaneously impressed upon the push-pull amplifying tubes 178 and 181, the oscillator frequency appears in the output windings 187 and 188 of the push-pull unit as a constant amplitude interrupted signal, the interruptions being produced in accordance with the output signal from the square wave amplifier unit, since, of course, the square wave amplifier signal does not modulate the carrier or tone frequency of the oscillator 143 in the push-pull unit but, because of the fact that this signal is supplied in such a manner as to appear substantially cophasally upon each of the grid elements 175 and 177, biases the push-pull tubes either to pass or block the oscillator frequency.

The useful output from the push-pull amplifier unit is transferred from the primary winding 189 of the transformer 141 through the secondary winding 183 which connects by way of conductors 185 and 187 to the terminals 188 and 201 which function as the output terminals either to the connecting line for line transmission or to the radio transmitter for radio transmission. In order to monitor the signal appearing in the output circuit of the push-pull amplifier unit, provision has been made by way of the transformer 143 for the primary winding 187 to feed energy into the secondary 181, and by inserting a suitable plug into the switch contact 203 the resulting output which is being directed to the line by way of terminals 188 and 201 may be determined.

In order to key the system by hand where hand keying is desirable, provision has been made by way of terminals 215 and 217 to energize the relay 223 by way of the winding 218 so as to cause the relay 223 to close, and, by moving the switch 131 to the left hand position from that shown, the hand-keyed signal may be arranged to control the output from the push-pull unit comprising the tubes 178 and 181.

In the circuit with the plate energy supply for the various tubes, provision is made for filtering and smoothing the plate energy supply by way of series-connected inductance elements 205 and shunt-connected capacities 207 which are grounded at 211. Each of the filament circuits connects at terminals 213 and 215 with the source of heating current and, as shown, all tubes are of the indirectly heated type, although it is to be understood that other type tubes may be substituted where desired.

From the above description, it is believed it will become apparent that the system is so designed as to cause the picture signals to produce constant frequency variable duration marking impulses which when reproduced at the point of reception will produce the general type of marking shown by Fig. 3a. Of course, it is to be understood that in any system of the type herein disclosed it is impossible to represent the exact type of markings which are produced by any hand-made drawing since the particular type of recording depends solely upon the characteristics of the controlling circuits and the marking instrumentality, or, in other words, any system

of the type herein disclosed is predicated upon such a theory that the method and apparatus disclosed will produce only the type of markings characteristic of the system, varied, of course, in accordance with tonal variations of the subject for transmission, and that the particular type of markings can be produced only by a system of the same nature. Therefore, while effort has been made to illustrate graphically the type of markings produced by the system, it nevertheless should be noted that such type of marking cannot be considered as a true and exact example of the quality of transmission obtainable but merely as being representative of the broad principles of the invention.

To produce markings of the general type shown by Fig. 3b, the screen tone frequency which is impressed upon the terminals 1 and 3 is, after each independent line of recording, reversed, that is, the phase is shifted by one hundred and eighty electrical degrees, so that the characteristic markings of the system are displaced by an amount equal to half of the time between each successive marking representations for the previous phase position of the screen frequency. Such an arrangement of shifting the phase of the screen frequency can be accomplished conveniently by an arrangement of the general type shown by Fig. 4. By this figure, the tone wheels 238 and 237 which are driven from the driving means 30 for rotating the picture record carrier are shown as provided with pick-up units 239 and 241 comprising a magnetic core 243 about which is placed a suitable winding 245 and 247 connected with conductors 249, 251 and 253, 255 leading to 35 switches 257 and 259 which in turn connect by conductors 261, 263 through the double-pole double-throw switch 265 with the output line directed to the terminals 1 and 3 of Fig. 1. By Fig. 4 only two separate pick-up units and tone 40 wheel generators for generating the screen frequency are shown, although it is to be understood that any suitable number of such generators, such as five or ten with suitable connecting switches, may be provided where it is desired to 45 have a wide range of flexibility in the system. In such case, each tone generator will be connected through a separate switch element, similar to that shown for the two tone wheel units to the connecting lines which lead to the output 50 terminals 1 and 3.

Mounted upon the record carrier is a cam unit 267 which, if the scanning unit is one which rotates continuously and is arranged to provide a relatively slow longitudinal movement between 55 the pick-up unit and the carrier, may be driven at a speed equal to half the speed of the record carrier, so that at the completion of each single rotation of the record carrier drum the switch element 268 may be closed by the cam. If the 60 scanning and reproducing systems are of the reciprocating rather than the rotary type, so that the scanning unit moves at a relatively fast rate longitudinally of the record and at a relatively slow rate across the record carrier, then the cam 65 element may be made to close the switch at the end of one stroke and to open the switch at the end of the stroke in the opposite direction. Connected to the terminals of the double setting unit, such as double-pole double-throw switch 265, actuated by the closure of the switch 269 by the cam 267, is a source of direct current which, when the switch 268 is closed by the cam 267, is adapted to actuate the relay winding 271 to change the position of the double-pole double-throw relay 70 75

switch 265 connected with the conductors 261, 263 leading from the pick-up units. The middle two terminals of the double-pole double-throw relay switch connect with the output lines leading to the terminals 1 and 3, whereas the outside terminals connect in reverse order with the conductors leading to the pick-up units and upon the position of the double-pole double-throw relay depends the direction of current flow through the conductors to the terminals 1 and 3. Therefore, at the end of each separate line of recording for each of the series of elemental areas or sections forming each line of the picture record the phase of the screen tone frequency is shifted by one hundred and eighty degrees, and thus the input frequency to the amplifier tube 18 is shifted. Consequently, the entire operation of the system comprising the converter unit in the form of the mixing tube and the square wave amplifier is reversed, so that the type of marking produced is changed from that shown by Fig. 3a, with no double setting, to that shown by Fig. 3b with double setting. This double setting feature, it will be seen, improves the detail of the picture to a considerable degree and provides an arrangement for resembling in the received record the usual half-tone print.

It is to be understood, of course, that while we have shown one suitable form of device for accomplishing the double setting, the invention is not restricted to the particular form shown but other suitable forms of arrangements for producing the effect of double setting may be used where desired, and the particular form of device shown is merely illustrated to complete the combination.

As disclosed by Fig. 5 of the drawings, a system for receiving the signals transmitted from the output of the arrangement shown by Fig. 1 may, for example, in the case of radio reception, consist of a plurality of spaced antenna systems 275, 277 and 279. These antennas are geographically separated so as to permit diversity reception in order to avoid the detrimental effects of fading and the like, as has been taught by Beverage and Peterson, for example in their U. S. Letters Patent, No. 1,874,866 issued August 30, 1932 and entitled "Method and means for eliminating fading on short wave lengths". Each antenna system is connected to a radio frequency amplifier which feeds its output into a detector stage from which the received energy is directed through an audio frequency amplifier and rectifier unit. Each of the rectifier units as receiving energy from the three separated antenna systems is arranged to feed the output energy in common across the first tube of a combining unit which is so arranged that the plate current flowing through the combining unit, as controlled by the rectified received signals in the combining unit 281, may be made to control or key a tone keyer 283. The tone frequency generated in the tone generator 285 is directed to the tone keyer unit 283, which includes a push-pull stage with the grids controlled as to potential by means of the combining unit output. The tone keyer is so arranged that the output energy from the combining unit, when a heavy current flows therethrough, produces through a high potential drop in a resistor element connecting the common connected filaments of the push-pull connected amplifiers and the center point of the transformer secondary, to the primary of which the tone frequency generated in the tone generator 285 is supplied, so that a large current

flowing in the plate circuit of the combining unit 281 tends to block the tubes of the tone keyer. The output of the tone keyer is directed through lines 287, 287 to an amplifier unit 288 which may be closely adjacent the tone keyer or remotely separated therefrom, if land lines are used to convey the signals from the tone keyer 283 to an amplifying unit 288 which is geographically separated from the tone keyer. The output energy from the amplifier 288 is directed through rectifier 291 to control the photoradio recording device 293 so as to reproduce the transmitted subject matter. This photoradio recording device may be of any suitable and well known type, for example, a device of the type disclosed by Richard Howland Ranger and constructed substantially in accordance with the teachings in U. S. Patent #1,803,133, granted April 28, 1931, although any other and suitable type of recording unit may be substituted where desired.

The invention as herein described does not refer to the application of the system for television transmission wherein there is no direct recording action at the point of reception but rather the image production is merely the production of visual images in contrast to real images such as are produced by actual markings. Nevertheless, it should be understood that the broad principle of the invention as herein set forth and defined is applicable to television as well as to the transmission of still pictures, and therefore throughout the claims defining our invention in its broadest terms the word "pictures" should be construed also as being capable of covering and relating to television transmission and reception of pictures.

While only a single form of the invention has been shown and described herein, it is nevertheless to be understood that the broad principle covered by the invention is capable of many modifications and changes, and therefore we believe ourselves to be entitled to make and use all of these modifications which suggest themselves to anyone skilled in the art to which the invention is directed so long as such modifications and changes fall fairly within the spirit and scope of the invention as defined by the hereinafter appended claims, wherein we claim and desire to secure by Letters Patent the following:

1. In the method of reproducing pictures or the like the steps which comprise electronically converting amplitude modulated carrier wave picture signalling impulses into rectified filtered energy and converting the rectified energy into constant amplitude constant frequency impulses and prolonging the duration of each impulse occurring at constant frequency for a time period directly proportionate to the variations in amplitude of the picture signals.

2. The method of electrically reproducing half tone prints from a record surface which comprises electronically converting changes in light intensity on elemental areas of the subject into amplitude modulated carrier wave signals converting the carrier wave signals into rectified filtered energy, and changing the amplitude variations of the rectified energy into signalling pulsations of constant frequency and amplitude each of a variable time duration directly proportionate to the amplitude of the picture signals.

3. The method of electrically reproducing half tone prints from a record surface which comprises electronically converting changes in light

intensity on elemental areas of the subject into amplitude modulated carrier wave signals converting the carrier wave signals into rectified filtered energy, and changing the amplitude variations of the rectified energy into signalling pulsations of constant frequency constant amplitude and variable time duration directly proportionate to the amplitude of the original signals.

10. 4. In the method of reproducing pictures or the like the steps which comprise electronically converting amplitude modulated carrier wave picture signalling impulses into rectified filtered energy and converting the rectified energy into constant amplitude constant frequency impulses, prolonging the duration of each impulse occurring at constant frequency for a time period directly proportionate to the variations in amplitude of the original signals, and keying a transmitter by said constant amplitude constant frequency variable duration signals.

5. The method of electrically reproducing half tone recordings from a record surface which comprises converting changes in light intensity upon elemental areas of the record subject into signalling impulses of varying amplitudes of carrier wave energy proportionate to the changes in light intensity, electronically producing from the varying amplitude signalling impulses rectified filtered energy, electronically converting the rectified energy into constant amplitude constant frequency impulses and causing each produced impulse occurring at constant frequency to continue for variable time durations directly proportional to the amplitude of the varying amplitude picture produced signals.

6. The method of electrically reproducing half tone recordings from a record surface which comprises converting changes in light intensity upon elemental areas of the record subject into signalling impulses of varying amplitudes of carrier wave energy proportionate to the changes in light intensity, electronically producing from the varying amplitude signalling impulses rectified filtered energy, electronically converting the rectified energy into constant amplitude constant frequency impulses, causing each produced impulse occurring at constant frequency to continue for variable time durations directly proportional to the amplitude of the varying amplitude signals produced, and keying a carrier frequency on and off completely from said constant frequency constant amplitude and variable duration signalling impulses.

7. The method of electrically reproducing half tone recordings from a record surface which comprises converting changes in light intensity upon elemental areas of the record subject into signalling impulses of varying amplitudes of carrier wave energy proportionate to the changes in light intensity, electronically producing from the varying amplitude signalling impulses rectified filtered energy, electronically converting the rectified energy into constant amplitude constant frequency impulses and causing each produced impulse occurring at constant frequency to continue for variable time durations directly proportional to the amplitude of the varying amplitude signals produced.

8. The method of electrically reproducing pictures which comprises producing constant frequency variable amplitude carrier wave electrical energy in which the amplitude variation is a function of the varying intensities of light and

shadow on elemental areas of the record of which an image is to be reproduced, independently producing a screen frequency of predetermined value and constant amplitude, rectifying the constant frequency variable amplitude picture signals, filtering the rectified signals, combining the rectified filtered picture impulses with the constant amplitude constant frequency screen frequency impulses, and producing electronically from the combined signals a series of constant frequency constant amplitude signals each of a width directly proportional to the variations in amplitude of the amplitude varying signals.

9. The method of electrically reproducing pictures which comprises producing constant frequency variable amplitude electrical energy in which the amplitude variation is a function of the varying intensities of light and shadow on elemental areas of the record of which an image is to be reproduced, independently producing a screen frequency of predetermined value and constant amplitude, rectifying the constant frequency variable amplitude picture signals, combining the rectified picture impulses with the constant amplitude constant frequency screen frequency impulses, producing from the combined signals a series of constant frequency constant amplitude signals each of a width proportionate to the variations in amplitude of the amplitude varying signals, and cyclically shifting the phase of the screen frequency through 180 electrical degrees to change cyclically the position of the marking impulses with the spacing periods.

10. The method of electrically reproducing pictures which comprises producing constant frequency variable amplitude electrical energy in which the amplitude variation is a function of the varying intensities of light and shadow on elemental areas of the record of which an image is to be reproduced, independently producing a screen frequency of predetermined value and constant amplitude, rectifying the amplitude controlled signalling impulses, combining the rectified picture signals with the constant amplitude constant frequency screen frequency impulses, producing from the combined signals a series of constant frequency constant amplitude signals each of a width proportionate to the variations in amplitude of the amplitude varying signals, generating a carrier frequency, keying the carrier frequency for transmission in such manner as to transmit the carrier frequency full strength during the time periods when the said constant amplitude constant frequency pulsations are produced and to interrupt the carrier frequency during the spacing periods between said constant frequency constant amplitude pulsations, and periodically changing, at predetermined time periods, the phase of the screen frequency to change cyclically the position of the marking with the spacing.

11. The method of electrically reproducing pictures which comprises producing constant frequency variable amplitude electrical energy in which the amplitude variation is a function of the varying intensities of light and shadow on elemental areas of the record of which an image is to be reproduced, independently producing a screen frequency of predetermined value and constant amplitude, combining the constant frequency variable amplitude signalling impulses with the constant amplitude constant frequency

screen frequency impulses, producing from the combined signals a series of constant frequency constant amplitude signals each of a width proportionate to the variations in amplitude of the amplitude varying signals, generating a carrier frequency and keying the carrier frequency for transmission in such manner as to transmit the carrier frequency full strength during the time periods when the said constant amplitude constant frequency pulsations are produced and to interrupt the carrier frequency during the spacing periods between said constant frequency constant amplitude pulsations, and changing, after predetermined periods, the phase of the screen frequency through an angle of substantially 180° to cyclically change the position of the marking pulses with the spacing.

12. In a system for electrically reproducing picture records, means for converting the varying intensities of light and shadow on elemental areas of the subject of which an image is to be reproduced into a train of amplitude varying carrier wave signals, means for rectifying the amplitude varying carrier wave signals, means to filter the rectified signals, spaced discharge means for converting the rectified filtered signals into electrical energy of constant amplitude and constant frequency, and means for controlling the time duration of the produced constant frequency constant amplitude signals in such manner that the signal is produced for a time period between each point of recurrence of the signal in direct proportion to the amplitude variation in the original signal.

13. In a system for electrically reproducing picture records, means for converting the varying intensities of light and shadow on elemental areas of the subject of which an image is to be reproduced into a train of amplitude varying signals, means for converting the amplitude varying signals into electrical energy of constant amplitude and constant frequency, means for controlling the time duration of the produced constant frequency constant amplitude signals in such manner that the signal is produced for a time period between each point of recurrence of the signal proportionate to the amplitude variation in the original signal, and means to cyclically interchange the signalling and spacing periods.

14. In a system for reproducing picture records, means for converting varying intensities of light and shadow on a record surface into amplitude varying electrical energy, means for modulating a tone frequency in accordance with said amplitude variations, means for producing a screen frequency of fixed relation to the scanning speed for determining the detail in the reproduced picture, means for rectifying the amplitude modulated tone frequency for producing pulsating direct current of amplitude proportionate to the picture modulation, means for combining the screen frequency with the pulsating direct current, thermionic means for producing from said combined signal energy a wave train of energy of constant frequency and constant amplitude with a duration of signalling portions directly proportional to the amplitude of the amplitude varying signals, means for generating a carrier frequency, and means for keying said carrier frequency for transmission by said constant frequency constant amplitude varying duration signals, whereby for marking periods the carrier frequency is transmitted con-

tinuously at full amplitude and for spacing periods the carrier frequency is interrupted.

15. In a system for reproducing picture records, means for converting at a predetermined rate the varying intensities of light and shadow on a record surface into amplitude varying electrical energy, means for modulating a tone frequency in accordance with said amplitude variations, means for producing a screen frequency of fixed frequency relation to the rate of scanning for determining the detail in the reproduced picture, means for producing from said amplitude varying picture signal frequencies pulsating direct currents, means for combining the screen frequency with said pulsating direct currents, and thermionic means for producing from said combined signal energy a wave train of energy of constant frequency and constant amplitude with a duration of signalling portions directly proportional to the amplitude of the amplitude varying signals.

16. In a system for reproducing picture records, means for converting at a predetermined rate the varying intensities of light and shadow on a record surface into amplitude varying electrical energy, means for modulating a tone frequency in accordance with said amplitude variations, means for producing a screen frequency of fixed frequency relation to the rate of scanning for determining the detail in the reproduced picture, means for producing from said amplitude varying picture signal frequencies pulsating direct currents, means for combining the screen frequency with said pulsating direct currents, electrical means for producing from said combined signal energy a wave train of energy of constant frequency and constant amplitude with a duration of signalling portions directly proportional to the amplitude of the amplitude varying signals, means for generating a carrier frequency, and means for keying said carrier frequency for transmission by said constant frequency constant amplitude varying duration signals, whereby for marking periods the carrier frequency is transmitted continuously at full amplitude and for spacing periods the carrier frequency is interrupted.

17. In a system for reproducing picture records, means for converting at a predetermined rate the varying intensities of light and shadow on a record surface into amplitude varying electrical energy, means for modulating a tone frequency in accordance with said amplitude variations, means for producing a screen frequency of fixed frequency relation to the rate of scanning for determining the detail in the reproduced picture, means for producing from said amplitude varying picture signal frequencies pulsating direct currents, means for combining the screen frequency with said pulsating direct currents, means for producing from said combined signal energy a wave train of energy of constant frequency and constant amplitude with a duration of signalling portions directly proportional to the amplitude of the amplitude varying signals, means for generating a carrier frequency, means for keying said carrier frequency for transmission by said constant frequency constant amplitude varying duration signals, whereby for marking periods the carrier frequency is transmitted continuously at full amplitude and for spacing periods the carrier frequency is interrupted, and a double setting means for cyclically changing the phase of the screen frequency through 180° to produce a cyclic change in the

position of marking and spacing indications to prevent a direct alignment of adjacent marking indications in the reproduced record.

18. In a system for electrically reproducing picture records, means for converting the varying intensities of light and shadow on successive elemental areas of the subject of which an image is to be reproduced into a train of amplitude varying carrier wave signals, means for rectifying the amplitude varying carrier wave signals, means to filter the rectified signals, space

discharge means for converting the rectified filtered signals into electrical energy of constant amplitude and constant frequency, and means for controlling the time period of separation between each signal pulse of the series of constant frequency impulses in direct proportion to the amplitude of the amplitude varying signals. 5
